Primary Examiner — Derrick Holland*Assistant Examiner* — Lauren Calve(74) *Attorney, Agent, or Firm* — QuickPatents; Kevin Prince(57) **CLAIM**

I claim the ornamental design for a stack of flooring tiles, as shown and described.

DESCRIPTION

FIG. 1 is an exploded perspective view of a stack of flooring tiles, showing my new design;

FIG. 2 is a perspective view thereof, a container of the design omitted for clarity of illustration;

FIG. 3 is a left-side elevational view of FIG. 2, the right-side elevational view being a mirror image thereof;

FIG. 4 is a top plan view of FIG. 2;

FIG. 5 is a bottom plan view of FIG. 2;

FIG. 6 is a front elevational view of FIG. 2, the rear elevational view being a mirror image thereof;

FIG. 7 is a perspective view thereof;

FIG. 8 is a left-side elevational view of FIG. 7, the right-side elevational view being a mirror image thereof;

FIG. 9 is a top plan view of FIG. 7, the bottom plan view being a mirror image thereof;

FIG. 10 is a front elevational view of FIG. 7, the rear elevational view being a mirror image thereof;

FIG. 11 is an exploded perspective view of a second embodiment thereof;

FIG. 12 is a perspective view of FIG. 11; and

FIG. 13 is a left-side elevational view of FIG. 11, the right-side elevational view being a mirror image thereof; and,

FIG. 14 is a top plan view of FIG. 11, the bottom plan view being a mirror image thereof.
